UNITED STATES PATENT OFFICE.

HOWARD M. DUDLEY, OF PHILADELPHIA, PENNSYLVANIA.

DYEING-MACHINE.

1,274,523.

Specification of Letters Patent. Patented Aug. 6, 1918.

Application filed June 1, 1917. Serial No. 172,170.

To all whom it may concern:

Be it known that I, HOWARD M. DUDLEY, a citizen of the United States, and a resident of Philadelphia, in the county of Philadelphia and State of Pennsylvania, have invented certain new and useful Improvements in Dyeing-Machines, of which the following is a specification.

My invention refers to dyeing machines and refers particularly to a machine suitable for the dyeing of worsted top and warp balls.

One object of my invention is a device whereby worsted top, warp balls and similar fibers may be thoroughly and evenly dyed and treated with liquids and air.

Another object of my invention is a device whereby fibers in the condition stated above may be dyed and treated without injury to the fiber.

Another object of my invention is a device whereby fibers in the condition stated above may be readily and rapidly packed into dyeing chambers and compressed into a form suitable for even penetration.

Another object of my invention is a device whereby a considerable number of balls, tops, &c., may be dyed equally.

These and other objects of my invention will be evident upon a consideration of my specification and claims.

The dyeing of worsted tops, warp balls and similar fibers presents several difficulties which must be overcome in order to produce even and satisfactory results.

On account of the physical condition of the fibers, they must not be disturbed during the dyeing operation but must be retained in their original untangled condition.

On account of the shape of the tops or balls, it is difficult to obtain satisfactory results by placing them in layers, each layer comprised of a number of tops or balls, as when compressed, channels or openings are liable to be formed between the tops and balls, as it is difficult to compress them all into a uniform mass for the passage of the liquid.

I have overcome all of these difficulties and the device of my invention will dye fiber forms of this character evenly and completely.

I have found that the even or uneven dyeing results obtained in a machine of this general character depend largely upon the particular shape of the openings through

which the dye liquor enters the fiber mass, and that unevenness can be prevented by the use of openings of a particular shape, the conformation of which enables the liquor to spread itself through the fiber mass without the formation of channels of flow.

I have further found that this desirable result may be enhanced by inclosing the fiber in a series of containers and passing the treating liquid through these containers and the fiber contained therein, first in one direction and then in the reverse direction.

In the use of many dyestuffs it is necessary, after dyeing to treat the dyed goods with water for washing purposes, or with solutions of chemicals such as metallic salts or oxidizing products, for the purpose of after-treatment, or with oxygen or air for oxidizing or drying purposes. In the following of these after-treatments it is essential that every portion of the dyed goods be thoroughly and uniformly treated and that the operation be performed as readily and quickly as possible. All of these results are obtainable by the use of the device of my invention, in which the goods are placed in the dyeing chamber and then rapidly, easily and completely dyed and after-treated without further handling of the goods and without the formation of channels by the liquids employed. The device therefore insures even and uniform results with a minimum of time, labor and expense.

One form of my invention is shown in the accompanying drawings in which similar parts are designated by similar numerals.

Figure 1 is a top plan view of one form of the device of my invention.

Figs. 1^A and 1^B illustrate certain pipe connections carried by the chambers of the pumps.

Fig. 2 is a side plan view of a portion of Fig. 1, partly broken away.

Fig. 3 is a cross-section through the line 3—3 of Fig. 1.

Fig. 4 is a cross-section through the line 4—4 of Fig. 2.

Fig. 5 is a broken cross-section illustrating one of the valves operating in one of the pipes leading to the testing machine.

Fig. 6 is a cross-section through the line 6—6 of Fig. 5.

Fig. 7 is a cross-section through the line 7—7 of Fig. 6.

Fig. 8 is a partial top plan view of one of the foraminous plates.

Fig. 9 is a cross-section through the line 9—9 of Fig. 8.

Fig. 10 is a development on line 10—10 of Fig. 8.

5 In the form of my device as illustrated in the accompanying drawings, the truck 20 is mounted upon the wheels 21, 21, which are capable of movement upon the tracks 22, 22. Pivotally mounted upon the truck 20, is a receptacle 23, fixedly attached to the pinion 24 which is revoluble within the frame 25. Fixedly attached to the pinion 24 is a toothed segmental wheel 26, meshing with the teeth of the worm 27. The worm 27 is revoluble within the supports 28, 28, mounted upon the truck 20 and is capable of revolution by revolving the wheel 29 fixedly attached to the shaft 30 of the worm 27. The turning of the wheel 29 therefore revolves the receptacle 23 through the medium of the worm 27 and the toothed wheel 26. The outer cylindrical wall of receptacle 23 is comprised of the shell 31 which extends upwardly and outwardly into 25 the members 32, 32^A, forming the cylindrical chambers 33, 33^A.

At the two ends of the receptacle 23 are the hollow members 64, 64^A extended into the hollow members 65, 65^A. The larger end 30 of each of the members 64, 64^A is of the same size and shape as the members 32, 32^A, upon which it is capable of abutment, and carries the angular collars 66, 66^A, capable of engagement with the annular member 70, 70^A 35 of the members 32, 32^A.

The method of attaching the members 64, 64^A to the shells 32, 32^A is as follows, as shown in Figs. 2 and 4: A compressible gasket 82, 82 is inserted between the pyramidal shaped flange members 66 and 70, the gasket being preferably formed of a number of pieces. The clamping member 59 is closed upon its hinge 60, the inclined inner faces of the clamping member abutting 45 upon the inclined outer faces of the flange members 66 and 70, and the joint between the two flange members made tight by the pressure carried by means of the thumbscrew 61.

50 Connected with the cylindrical chambers 33, 33^A are the pipes 34, 34^A carrying the valves 35, 35^A and converging into the pipe 36 which enters the upper portion of the tank 37.

55 The receptacle 23 also carries the pipe 117 with the valve 118.

The centrifugal pumps 71, 71^A are connected at their discharge ends with the members 65, 65^A by means of the pipes 120, 120^A 60 carrying the valves 121, 121^A. The charging ends of the pumps 71, 71^A are connected with three-way pipes 73, 73^A, which three-way pipes are connected with the pipes 74, 74^A carrying the valves 75, 75^A, the pipes 76, 76^A 65 carrying the valves 77, 77^A and the pipes 78,

78^A carrying the valves 79, 79^A. The pipes 74, 74^A lead to a source of water supply, the pipes 76, 76^A lead to the bottom of the liquid reserve tank 37, which is situated above the pumps 71, 71^A and the pipes 78, 78^A lead to 70 a tank containing the liquid in which the dye is dissolved. Connected with the pumps 71, 71^A respectively are the two-way pipes 85, 85^A, branching into the pipes 86, 86^A carrying the valves 87, 87^A and opening into the 75 air, and the pipes 88, 88^A carrying the valves 89, 89^A, connected with an exhaust and compression pump not shown.

Within the conical members 64, 64^A are the imperforate conical members 80, 80^A, capable of abutment upon the imperforate cylindrical member 116 which is situated within the receptacle 23. The members 80, 80^A are supported by the bar supports 81, 81^A. 80

Within the receptacle 23 are a series of hollow cylindrical chambers 90, 90, having imperforate side walls 91, the ends being open. Within one end of each of the hollow cylindrical chambers 90, 90 is a foraminous plate 92, resting upon the annular abutment 93. Within the other end of the chamber 90 is a slidably movable foraminous plate 94, which is moved by the revolution of the threaded member 95 which is meshed 95 with the threads 96 within the chamber 90, the member 95 being capable of abutment upon the plate 94. 90

Within the exterior wall of each cylindrical member 90 are the conduits 100, 100^A, 100 carrying the valves 101, 101^A. The construction of these valves is shown in Figs. 5, 6 and 7. The stem 102 has the one-way port 103, the pin 104 is inserted in the groove 105 to prevent the withdrawal of the valve-stem 102, and the stop-pin 106 sets the valve for the free passage of liquid through the conduit 100^A or for the complete stoppage of such passage. 105

Within the wall of each cylinder (see 110 Figs. 5, 6 and 7) is a chamber 107, into which the conduits 100, 100^A lead, said chamber being threaded upon its inner surface. A threaded cap 108, capable of enmeshment with the threads of the chamber 107, is slidably movable over the testing tube 109. In order to insert the testing tube 109, the two caps 108, 108 are slid inwardly upon the testing tube, the tube inserted between the two openings of the conduit 100, 100^A, and 115 the two caps 108, 108 threaded with the threads of the chamber 107 and screwed inwardly until a tight joint is effected by means of the gasket 110. 120

Each of the foraminous plates 92 and 94 125 is comprised of a series of concentric rings carrying upwardly 111, 111 and downwardly 112, 112 extended pointed members, between which are openings 113, 113 for the passage of liquor. 130

Perforated steam pipes 115, 115^A are within the chambers 33, 33^A.

The operation of the device is as follows, assuming that the dyeing or treating operations have been finished and the device in the position shown in the drawings: All of the valves with the exception of 118 are closed, thus drawing off the liquid within the receptacle. The pipe 36 is then uncoupled. The series of screw-bolts 61, 61 are withdrawn, the clamping members 59, 59 opened and the gaskets 82, 82 removed, thus freeing the receptacle 23 from engagement with the members 66, 66^A. Truck 20 is then 10 withdrawn from its position by rolling it upon the tracks 22, 22, thus removing the receptacle from between the conical members 64, 64^A. The receptacle 23 is then given a quarter revolution by turning the wheel 15 29, and may be maintained in this position, if necessary, by means of the screw bolt 130. The members 95, 95 are screwed out of position, and the fiber 131, 131 is removed.

When it is desired to load the device, a 25 set of tops or balls 131, 131 is inserted within each cylindrical chamber 90, a foraminous plate 94 inserted within the chamber and pressed downwardly upon the fiber by screwing in the member 95. When each chamber 30 90 is thus loaded and packed, the device is revolved into an upright position, rolled in between the members 64, 64^A, and tightly joined thereto by means of the gasket 82 and the clamping members 59, 59.

35 The apparatus is so arranged that the treating liquid may be passed in either direction through the fiber. To dye, all the valves are closed with the exception of 77^A, 91^A, 35, 101 and 101^A, and the pump 71^A 40 started. This draws the liquid from the tank 37 through the pipe 76^A and forces it through the pipe 65^A, the conical chamber 64^A, and thence through the chamber 33^A, the foraminous plate 92, the chambers 90, 45 90 and the fiber 131 therein. From thence the liquor passes through the foraminous plate 94, the chamber 33 and the pipes 34 and 36 back into the tank 37. At the same time, the liquor is forced through the conduit 100^A, the testing tube 109, the conduit 100 into the chamber 33 and from thence back into the tank 37.

When it is desired to reverse the flow of liquid the pump 71^A is stopped and all the 55 valves closed with the exception of 77, 121, 35^A, 101 and 101^A and the pump 71^A is started.

When the dyeing operation is completed 60 the liquor in the dyeing chamber is removed by allowing it to drain through the pipe 117 by opening the valve 118 at the bottom thereof.

If it is desired to wash the goods, water 65 is admitted through the pipes 74, 74^A by opening the valves 75 and 75^A, and the water

forced through the device and the goods contained therein, the other valves being in such an open or closed position as to cause the water to enter either through the pipe 74 or 74^A and exit through the other one, the 70 circulation being caused by either the pump 71 or 71^A.

If it is desired to treat the dyed fiber with air, the valves 87 and 89^A and the exhaust pump (not shown) started, the other valves 75 being arranged to allow air to be sucked in through the pipe 86, the device and fiber, by the suction upon the pipe 88^A, or by using the compression side of the pump (not shown) air may be forced through the device and the fiber in an opposite direction from that just described.

During all of these operations the valves 101 and 101^A are maintained in an open condition, thus allowing the fiber in the 85 smaller device 109 to receive exactly the same treatment as that in the larger device, and the condition of the fiber in the larger device may be determined at any time without interrupting the process by closing the 90 valves 101, 101^A and examining the fiber in the smaller device 109, by unscrewing the members 108, 108 and removing the test tube 109 for examination.

One of the chief improvements in my device is the method whereby the dyeing chamber and its contents may be removed from the source of liquid supply without the necessity of handling, or moving the latter, thus effecting a very considerable saving in 100 time of operation and cost of erection, and in presenting a method whereby a number of dyeing chambers may be employed in an exactly similar manner.

I do not limit myself to the particular 105 size, shape, number or arrangement of parts as described and illustrated, all of which may be varied without going beyond the scope of my invention as described and claimed.

What is claimed, is:

1. In a dyeing machine, in combination, a receptacle, a series of dyeing chambers having imperforate sides within the receptacle, each dyeing chamber having a fixed foraminous bottom and a movable foraminous top, means for moving the top with respect to the bottom, and for maintaining the top at any predetermined position with respect to the bottom, a chamber at each end 115 of the receptacle abuttable thereon, means for circulating a liquid through the end chambers and the dyeing chambers, means for removing the receptacle from between the two end chambers and means for revolving the receptacle when removed from between the end chambers.

2. In a dyeing machine, in combination, a receptacle, a series of dyeing chambers having imperforate sides within the recep- 130

tacle, each dyeing chamber having a fixed foraminous bottom and a movable foraminous top, means for moving the top with respect to the bottom, and for maintaining the top at any predetermined position with respect to the bottom, a conduit within the wall of each dyeing chamber connecting the portion of the receptacle at each end of the dyeing chamber with a testing device, a testing device the contents of which are capable of examination without interrupting the dyeing operation, a chamber at each end of the receptacle abuttable thereon, means for circulating a liquid through the end chambers and the dyeing chambers, means for removing the receptacle from between the two end chambers and means for revolving the receptacle when removed from between the end chambers.

20 3. In a dyeing machine, in combination, a receptacle, a series of dyeing chambers having imperforate sides within the receptacle, each dyeing chamber having a foraminous bottom with inwardly extended members and a foraminous top with inwardly extended members, means for maintaining the top and bottom at predetermined positions with respect to each other, a chamber at each end of the receptacle capable of abutment thereon, means for passing a liquid through the end chambers and the dyeing chambers, means for removing the liquid after it has passed through either end chamber and the dyeing chambers, means for removing the receptacle from abutment with the end chambers and means for revolving the receptacle.

4. In a dyeing machine, in combination, a receptacle, a series of dyeing chambers having imperforate sides within the receptacle, each dyeing chamber having a fixed foraminous bottom and a movable foraminous top, means for moving the top with respect to the bottom, and for maintaining the top at any predetermined position with respect to the bottom, an imperforate member between the dyeing chambers, a chamber at each end of the receptacle, capable of abutment thereon, means for forcing a liquid through either end chamber and the receptacle, means for removing the liquid from the receptacle, means for passing air through the receptacle and the dyeing chambers, means for removing the receptacle from abutment with the end chambers and means for revolving the receptacle to allow of the removal of the contents of the dyeing chambers.

5. In a dyeing machine, in combination, a receptacle, a series of dyeing chambers having imperforate sides within the receptacle, each dyeing chamber having a fixed foraminous bottom and a movable foraminous top, means for moving the top with respect to the bottom, and for maintaining the top at any predetermined position with respect to the bottom, an imperforate member between the dyeing chambers, a chamber at each end of the receptacle, capable of abutment thereon, a divergent imperforate member in each end chamber capable of abutment upon the imperforate member in the receptacle, means for passing a liquid through the end chambers and around their imperforate members and from thence through the receptacle and the dyeing chambers, means for removing the liquid from the receptacle and returning it producing a circulating system of the liquid, means for removing the receptacle from abutment with the end chambers, and means for revolving the receptacle after such removal to allow the withdrawal of the contents of the dyeing chambers.

6. In a dyeing machine, in combination, a receptacle, a series of dyeing chambers having imperforate sides within the receptacle, each dyeing chamber having a foraminous bottom with inwardly extended members and a foraminous top with inwardly extended members, means for maintaining the top and bottom at predetermined positions with respect to each other, an imperforate member between the dyeing chambers, a chamber at each end of the receptacle abuttable thereon, a divergent imperforate member in each end chamber capable of abutment upon the imperforate member in the receptacle, a conduit within the wall of each dyeing chamber connecting the portion of the receptacle at each end of the dyeing chamber with a testing device, a testing device the contents of which are capable of examination without interrupting the dyeing operation, a pump, means whereby the pump will force a liquid through the end chambers, the receptacle, the dyeing chambers and the testing device, means for returning the liquid to the pump, means for removing the receptacle from abutment upon the end chambers and means for revolving the receptacle.

Signed at New York, in the county of New York and State of New York, this 17th day of May, 1917.

HOWARD M. DUDLEY.
